[57] CLAIM

The ornamental design for a combined clock dial and hands, substantially as shown and described.

DESCRIPTION

FIG. 1 is a front elevational view of a combined clock dial and hands showing my new design;

FIG. 2 is a left side elevational view thereof;

FIG. 3 is a right side elevational view thereof;

FIG. 4 is a rear elevational view thereof;

FIG. 5 is top plan view thereof;

FIG. 6 is a bottom plan view thereof; and

FIG. 7 is a front elevational view of a second embodiment of my new design of FIGS. 1-6 all other views of this embodiment are substantially identical to FIGS. 2-6.

The broken-line showings of a clock motor in FIGS. 2-6 are environmental only and form no part of the claimed design.

FIG. 1

FIG. 2

FIG. 3

Fig. 4

Fig. 5

Fig. 6

FIG. 7
